DRILL PIPE WIPER

Gerald R. Hunt, Long Beach, Calif.

Application August 27, 1956, Serial No. 606,305

2 Claims. (Cl. 15—210)

This invention relates to a wiper to engage and act upon parts engaged in a well and is more particularly concerned with a wiper for use in connection with elements of a well at the top or head thereof and which serve to engage a string of drill pipe engaged or entered in the well in order to wipe or strip material such as drilling mud therefrom in the course of being pulled or withdrawn from the well. It is a general object of this invention to provide a wiper construction or device of the general character referred to that can be easily and conveniently engaged in operating position, a structure which is highly effective in operation and which is both easy and economical of manufacture.

Wipers are commonly employed in connection with pipes engaged in wells for the purpose of wiping material such as drilling mud and oil from the pipe as it is withdrawn from the well and to incidentally check accidental introduction of small hand tools into the well which might otherwise occur if the upper end of the well is open and unobstructed.

The usual wiper is characterized by a simple unitary disc having a central opening or hole therein to slidably receive and pass the drill pipe. The outer diameter of the disc is substantially greater than the well elements with or between which the wiper is engaged. The outer peripheral portion of the ordinary wiper is reinforced as by a metal ring so that when it is in use it will not collapse and can float freely between the well parts between which it is located without being fixed or attached to any one or more of the well parts.

It frequently happens that ordinary wipers become worn or torn, rendering them ineffective, with the result that they may have to be replaced during the operation of pulling a drilling string from a well. Furthermore, the ordinary wiper construction as above described, involves a large quantity of material which makes it a costly item to manufacture and replace.

It is a general object of my invention to provide a wiper construction to be related to one or more elements of a well structure and including an outer reinforced carrier ring and an inner expendable work engaging wiper element.

A further object of this invention is to provide a wiper construction of the general character referred to having a novel reinforced means for the carrier ring and a novel coupling means between the carrier ring and the wiper element.

It is another object of this invention to provide a carrier ring which is strong and durable and a wiper element which is of minimum size and is such that it is light, simple, and inexpensive of manufacture.

The various objects and features of my invention will be fully understood from the following detailed description of a typical preferred form and application of my invention, throughout which description reference is made to the accompanying drawings, in which:

Fig. 1 is a view illustrating the top of a well showing

2

the upper end of a casing, a rotary unit and drilling pipe extending through the unit and into the casing, parts being broken away to show in section, and a wiper construction of the present invention being shown in operating position.

Fig. 2 is an enlarged plan view of the wiper construction that I provide apart from the other elements of the well structure and having a portion thereof broken away to show in section.

Fig. 3 is an enlarged transverse sectional view of a portion of the wiper construction shown in Fig. 2 and taken substantially as indicated by line 3—3 on Fig. 2.

Fig. 4 is a transverse sectional view of the wiper construction showing it engaged on a pipe and apart from the other elements of the well structure.

Fig. 5 is a plan view of the wiper construction provided by the present invention and showing it engaged on a pipe and apart from other elements of the well structure.

The wiper construction provided by the present invention is adapted to be used in connection with well parts and/or elements, and it is intended to serve as a wiper for removing mud, oil, or other material from a string of drill pipe, or the like, extending from the well casing. The well structure in conjunction with which the wiper is employed may involve elements such as a well casing, or the head structure on a casing, a rotary unit and/or other like parts of the structure.

In Fig. 1 of the drawings, I have shown my wiper construction engaged with elements of a typical well structure employed during drilling operations. For instance, I have shown a casing 10 terminating below a rotary unit R, and a string S of drill pipe is shown engaged through the rotary unit and entering the casing 10.

The rotary unit R, illustrated, shows a typical structure of this general character and is shown as involving a base 11 supporting a table 12 through a suitable bearing 13, while a master bushing 14 is carried in the table establishing a central opening 15 concentric with the casing 10. The opening 15 is typical of the opening found in rotaries and is designed to receive slip bushings which are distinguished from master bushings by being relatively light, simple, and easy to handle and in practice, the slip bushings, not shown in the drawings, are frequently arranged in and removed from the table, whereas the master bushing 14 is commonly left in the table over long periods of time.

The wiper construction W provided by the present invention is shown as including an annular carrier ring 20 and a disc-shaped wiper element 21 carried by the ring 20 and having a central opening 22 passing the pipe S. In practice, the ring 20 and wiper 21 may be formed of rubber. It is to be understood that in referring to the ring 20 and wiper 21 being formed of rubber, it is intended to include rubber substitutes or rubber-like compositions. In practice, I prefer to employ a so-called synthetic rubber which is not appreciably affected by oil or the like. This type of material is desirable in the situation illustrated in that the material wiped from the string is often laden with oil.

In addition to the above, the wiper construction W provided by the present invention further includes a novel reinforcing means 23 for the carrier ring 20 and a novel coupling means 24 releasably securing the wiper element 21 in working relationship with the carrier ring.

The mounting ring 20 that I provide is a simple material body of rubber freely engaged around the string S of drill pipe to occur between the rotary unit R and the casing 10. The ring 20 is shown as having flat horizontally disposed top and bottom walls 25 and 26 and substantially vertically disposed inner and outer peripheral walls 27 and 28. The ring is larger in outside diameter

than the lower end of the master bushing 14 and is smaller in inside diametric extent than the opening 15 in the said bushing.

With the above relationship of parts, it will be apparent that when the wiper construction W is in operation and the string S is being elevated or withdrawn from the tubing 10, the mounting ring 20 engages and is held against vertical movement and displacement by the master bushing 14 of the rotary unit R.

The reinforcing means 23 for the carrier ring 20 is adapted to provide the ring with sufficient strength and rigidity so that the ring will not collapse or yield when it is urged into bearing engagement with the master bushing 14 and in such a manner as would permit the wiper construction W from being drawn through the opening 15 of the bushing and out of working position.

The reinforcing means 23 is shown as including a flat horizontally disposed coil 29 of spring steel rod or wire and a plurality of circumferentially spaced clips 30 engaging and holding the adjacent portions of the coil 29 in fixed relationship to each other. The wire coil 29 with the clips 30 is in the nature of an annular core in the ring 20 and is imbedded in the mass or body of rubber establishing the ring to occur midway between the top and bottom surfaces 25 and 26 of the ring and in spaced position between the inner and outer peripheral walls 27 and 28 thereof.

In practice, the ring 20 is established by a suitable molding operation and the coil 29 is engaged in the ring 20 during the molding operation with the result that the rubber establishing the ring flows around and is bonded to the coil. In the preferred carrying out of the invention, it is desirable that the adjacent portions of the wire or rod establishing the coil 29 be spaced radially apart from each other a slight distance so as to permit the rubber, during the formation of the ring, to flow therebetween.

It will be apparent that the reinforcing means 23 that I provide is highly effective to stiffen the ring 20 against collapsing or the like and yet is such that it can yield slightly when excessive forces are applied thereto. This feature is highly significant since it materially reduces the possibility of the ring becoming damaged and/or mutilated under severe working conditions and increases the effective life of the carrier ring.

The clips 30 of the means 23, adapted to maintain the coil 29 in proper coiled condition, are shown as simple radially inwardly opening and horizontally disposed U-shaped members formed of strip steel and having upper and lower legs 31 and 32 engaging or occurring adjacent the upper and lower sides or surfaces of the coil 29. In the preferred carrying out of the invention, the ends of the legs 31 and 32 of the clips 30 project radially inwardly from the coil 29 a substantial distance and establish a part of the coupling means 24 as will herein-after be described.

The disc-shaped wiper element 21 of my construction, carried by the ring 20 and having a central opening 22 therein to receive and pass the string of drill pipe S, is characterized by flat horizontally disposed top and bottom surfaces 33 and 34 and a substantially vertically disposed outer peripheral wall 35.

The central opening 22 extending through the wiper element 21 is slightly smaller than the outside diameter of the pipe S with the result that it establishes snug engagement therearound. In practice, the wiper element is formed of rubber or other like material that is sufficiently resilient to allow for expansion of the wiper so that joints J or on the pipe S may be passed through the wiper in the course of pulling the string S vertically from the well casing 10.

The wiper element 21 is substantially smaller in outside diameter than the inside diameter of the ring 20 so that it can be freely engaged within the ring with substantial working clearance, as clearly illustrated in the drawings.

The wiper element is preferably slightly less in vertical extent or thickness than the ring 20 so that when it is engaged in the ring and is connected thereto by the coupling means 24, it is maintained in spaced relationship between the top and bottom surfaces 25 and 26 of the ring and does not project therefrom where it could become damaged.

The coupling means 24 securing the wiper element 21 in working relationship with the carrier ring 20 includes a plurality of horizontally disposed and circumferentially spaced eyes 36 fixed to and projecting radially outwardly from the wiper member 21, a plurality of radially inwardly opening recesses 37 in the carrier ring 20 and freely receiving the eyes on the wiper member, a plurality of vertically disposed openings 38 through the ring and intersect the recesses, and a retainer pin 39 is engaged in each opening to extend through the recesses 37 related thereto and through the eyes 36 of the wiper element 21 engaged in the recesses.

In the preferred carrying out of the invention and as illustrated in the drawings, the eyes 36 are established by horizontally disposed metal rings or loops and are secured to the wiper 21 by radially outwardly projecting lugs 139 on the outer peripheral wall 35 of the wiper element. In practice, the wiper element 21 is formed by a suitable molding operation at which time the lugs 139 are established thereon with the loops or rings establishing the eyes 36 engaged therein.

The carrier ring 20 is provided with a radially inwardly opening notch 40 adjacent each recess 37 to freely receive the lugs 139 projecting from the wiper element.

In practice, the inner engaged relationship of the lugs on the wiper element in the notches in the carrier ring serves to facilitate orienting the wiper element in the carrier ring and also serves to interrupt the annular space between the wiper element and the carrier ring so as to prevent or restrict the passage of small tools and the like therebetween.

In practice, the clips 30 of the reinforcing rings 23 for the carrier rings are spaced circumferentially of the ring so that the radially inwardly projecting legs 31 and 32 project into the recesses 37 of the coupling means 24 and occur adjacent the upper and lower walls of the recesses.

The legs 31 and 32 of the clips are provided with openings 41 which register with the opening 38 in the ring to receive the retainer pins 39. With this relationship of parts it will be apparent that the retainer pins 39, engaged through the recesses in the ring 20 and serving to maintain the eyes 36 of the wiper element 21 engaged in the recesses 37, are coupled with the reinforcing coil 29 in the carrier ring through the clips, and are not subject to being pulled or torn out of engagement with the ring 20 when the structure is in operation.

The retainer pins 39 are preferably formed of soft malleable material and are provided with heads 42 at one end. The pins are engaged in the ring 20 to extend through the clips 30 and the eyes 36, and have their free ends bent to prevent them from dropping out or being accidentally displaced from the ring. In the case illustrated, the openings 41 in the clips 30 slidably receive the shanks of the pins 39 but will not pass the heads 42 thereof while the openings 38 in the ring 20 are of sufficient diameter to freely receive the heads of the pins.

With this relationship of parts it will be apparent that the heads of the pins 39 engage and establish metal-to-metal contact with the clips 30 and are completely recessed in the ring 20 so that they are not subject to becoming worn or damaged when the wiper construction is in operation, as clearly illustrated in the drawings.

In the case illustrated and to facilitate bending the free ends of the shanks of the pin 39, either for the purpose of making them fast or for the purpose of removing them, and also to protect them from being damaged or from creating a hazard when the structure is in operation

I have shown the upper or top surface 25 of the ring 20 provided with an elongate recess 45 adjacent each opening 38 in the ring and adapted to receive and accommodate the shanks of the retainer pins 39 when they are bent. In practice, similar recesses could be provided in the lower surface 26 of the ring 20 if desired and in which case the pins 39 could be inserted into working engagement from either the top or the bottom side of the ring.

From the foregoing description it will be apparent that the coupling means 24 is free or sloppy and allows for considerable play or movement between the carrier ring and the wiper element. As a result of the play between the rigid or stiff reinforced carrier ring and the yielding or flexible wiper element, the wiper construction W that I provide can be subjected to and withstand severe working conditions which would rapidly mutilate and/or wear out the ordinary one piece wiper construction.

In Fig. 4 of the drawings I have illustrated how the wiper element 21 can flex and shift relative to the carrier ring 20 in a vertical plane, while in Fig. 5 I have illustrated how the wiper element 21 can flex and shift relative to the carrier ring in a horizontal plane.

In practice, when the wiper element 21 becomes worn or mutilated, it can be easily and conveniently disconnected from the carrier ring 20 by removing the retainer pins 39. The wiper element removed can then be replaced by a new one by simply reversing the operation set forth above. It will be further apparent that in cases where the size of the drill pipe is changed and a wiper element having a central opening of a different size must be employed, a wiper element of proper size can be easily and advantageously engaged with the carrier ring in the manner set forth above and without requiring replacement of the wiper ring.

In the particular form of the invention illustrated and to prolong the service life of the carrier ring and to reduce the frictional drag between the ring and the master bushing 14, I have provided a plurality of circumferentially spaced upwardly projecting wear-receiving ribs 50 on the upper surface 25 of the carrier ring as clearly 40 illustrated throughout the drawings.

Having described only a typical preferred form and application of my invention, I do not wish to be limited or restricted to the specific details herein set forth, but

wish to reserve to myself any variations or modifications that may appear to those skilled in the art and fall within the scope of the following claims:

Having described my invention, I claim:

- 5 1. A wiper for an object extending through an opening in a rotary located above a well including, a continuous annular bodily expandable wiper member of flexible material defining a central opening and adapted to slidably pass the object, a continuous annular carrier ring of rubber surrounding the wiper element with working clearance and adapted to engage the underside of the rotary, reinforcing means in the carrier ring, and coupling means securing the wiper member to the carrier ring for limited axial and radial movement therebetween, said reinforcing means including a flat coil of metal rod and a plurality of circumferentially spaced clips engaging the coil and maintaining adjacent portions of the coil in spaced relationship to each other, said coupling means including a plurality of circumferentially spaced eyes projecting from the wiper member and engaged in the clips of the reinforcing means.
- 10 2. A wiper for an object extending through an opening in a rotary located above a well casing including a disc-shaped wiper element of flexible material expandable as a whole and having a central opening slidably passing the object, a rigid annular carrier ring surrounding the wiper element with clearance and adapted to engage the underside of the rotary, and coupling means including circumferentially spaced lugs on the exterior of the wiper element, circumferentially spaced notches on the inside of the carrier ring and receiving the lugs, radially inwardly opening recesses in the notches, radially outwardly projecting eyes on the lugs and extending into the recesses, and retainer pins carried by the carrier ring and extending through the recesses and the eyes engaged therein.
- 15
